UNITED STATES PATENT OFFICE.

CHARLES H. COCHRANE, OF NEW YORK, N. Y.

GAS-HEATING DEVICE FOR PRINTING PRESSES.

Application filed June 20, 1923. Serial No. 646,553.

To all whom it may concern:

Be it known that I, CHARLES H. COCHRANE, a citizen of the United States, and resident of New York city, in the county of New York and State of New York, have invented certain new and useful Improvements in Gas-Heating Devices for Printing Presses, of which the following is a specification:

10 In applying gas heat to printing presses it has been customary to use an iron pipe, with a row of uniform size flame-holes, such gas pipe extending across and below the path of the paper, so that when the freshly 15 printed sheet or web of paper was moved along it passed close above or right through the row of flame. This method of course involved much danger of paper-burning, to overcome which a number of automatic cut-offs have been invented to shut off the gas 20 when the printing press stopped, and re-light it automatically when the press started again, through the medium of a pilot light. Such mechanism are shown in my own Patent, No. 1,414,399, in Smith's Patent, No. 25 1,286,132, in Garling's Patent, No. 1,413,719, and in others that are well known.

In practice, each of these devices has some 30 drawbacks, and paper-burning is common in the pressrooms where they are used. To overcome these difficulties, I have devised a form of heating apparatus that gives much increased safety, and at the same time permits more heat to be transferred to the paper, when desired.

I make a reflecting gas heater, located above instead of below the freshly printed sheets or paper-web, in the printing press, or its extension or deliveryboard, and by employing two parallel rows of flame-holes in the gas pipe, and directing the flame against a broad steel shield, I am able to produce a far wider area or zone of heat through which the sheet passes, and without exposing the sheet directly to the flames.

But to make the mechanism doubly safe, and to save wasting gas I provide also an automatic gas cut-off working on a novel principle; the pinching of a rubber tube. 50 There are minor matters of improved construction that will appear from the annexed drawings and description.

The objects of the invention are:

1. To increase safety in the use of gas heat on printing presses;
2. To increase the heat available for rais-

ing the temperature of the paper, thus removing any charge of static electricity, and hastening the drying or setting of the ink;

3. To secure an even and uniform distribution of heat over the entire surface of the paper;

4. To provide an improved and simplified gas cut-off, saving gas and still further increasing safety;

5. To provide a heater for a printing press, that is easily and quickly removable, adjustable to a great variety of positions, and quickly swung or slid out of the way when desired.

These and other objects I attain by the following described mechanism.

Referring to the accompanying drawings, in which the letters refer to similar parts throughout the several drawings:

Fig. 1 represents a side elevation of the invention.

Fig. 2 represents a plan view of the invention.

Fig. 3 represents a cross-section along line 3—3 in Fig. 1.

Fig. 4 represents a variant form of suspension or support.

Fig. 5 represents another variant form of suspension.

Fig. 6 represents a perspective view of the heater-pipe with the double parallel row of flame holes.

Fig. 7 represents a sectional side view of the gas cut-off.

Fig. 8 represents a cross-section along line 2—2 in Fig. 7.

Fig. 9 represents a cross-section along line 1—1 in Fig. 7.

Fig. 10 represents a variant form of cut-off in cross-section.

No attempt is made to illustrate the mechanism of a printing press to which the heater is attached, or may be suspended over, as these are built in almost endless forms.

Referring particularly to Figs. 1 and 2, "A" is a telescopic standard for supporting the horizontal pipe support "B," from which the heater proper is suspended by the arms "C" and "C'". The heater may be swung to any point in a circle from the standard, by having the pipe elbow "D" slightly loose. "A¹" is a circular base to be bolted to the floor. "A²" is a telescopic pipe, and "A³" a thumb screw to hold it in place. "E" is the cut-off mechanism, shown

in detail in Figs. 7, 8, 9, and 10. The arms "C" and "C'" are fixed on the pipe "B" by set screws "F" and "F'". The heater can be adjusted to right or left on the pipe 5 "B" or it may be rotated to any desired angle. "L" is the freshly printed paper, such as is usually stacked a sheet at a time on the delivery board of a printing press.

Referring to Figs. 3 and 4, the gas pipe 10 "G" has two parallel rows of flame holes, which should be uniform in size and spacing, and preferably staggered, and so positioned with reference to the steel reflector "H", that the steel surface serves as a 15 baffle plate to spread the flame over the entire under surface. In practice the shields should be rectangular, and 10 or more inches wide, affording an area of reflected heat below that will uniformly 20 heat an entire sheet or web of paper. A web of paper passing under this heater is exposed to the heat approximately twenty times as long as one passing over the common type of open-flame gas pipe heater, 25 which delivers a line of heat over about one half inch. The steel sheet reflector "H" has its edges "I" turned down at right angles, and one or more braces, as "J", are used to stiffen the structure.

30 In Fig. 4 the heater is shown suspended by telescopic arms from the ceiling. Obviously it may also be raised and lowered by any suitable means known in practice. Fig. 5 shows a variant method by which the 35 heater may be attached to some convenient part of the printing press, as "K".

Referring to Figs 7, 8, 9, and 10, "a" is a portion of the gas pipe, with two rows of flame holes, "b" is the casing of the attached cut-off, "c" is the end of a flexible gas tube, supplying gas fuel to the metal tube "d", which is closed at its lower end; "e" is a short tube or nipple, connecting with "d", on which an india rubber tube "f" is fitted. "e'" is another short tube or nipple, connecting with the other end of "f", and terminating in a gas tip "g", within the heater pipe "a".

The lever of the cut-off mechanism is at 50 "h", and when the cut-off is open it will be understood that the gas flows uninterruptedly from the source through "c", "d", "e", "f", "e'", and "g", into "a". The lever "h", hinged to the casing at "i", Fig. 9 has a 55 vibrating movement, as indicated by the dotted line "j"; when closed, as in Fig. 9, it compresses and closes the india rubber tube "f", against its support "i"; "k" is a screw and "l" is a wire or cord for connecting the lever 60 to a movable part of the printing press as "m". Thus the movement of the part "m" in the direction of the arrow (Fig. 9) may be utilized to close the cut-off and stop the flow of gas through the tip to the heater.

65 That the heater may be re-lighted auto-

matically when the part "m" moves oppositely to the arrow and turns the gas on again, a by-pass "n" is provided, which takes in gas continually at "n'" and delivers it at "o", which being lit, constitutes a pilot-light for re-lighting the gas and air mixture that flows out of the holes "p", of the gas pipe heater; "q" is a hole in the nipple "r" (that joins the casing to the heater) to admit air, for mixing with the gas, on the well known Bunsen burner principle, this 75 constituting an air mixer.

In the variant form of cut-off (Fig. 10) a spiral spring "s" tends to lower the lever "h", closing the gas aperture in "f" which 80 may be opened by a pull on the wire "l", through the movement of the press-part "m".

It will be observed that this is the reverse of the action of the form shown in Fig. 9, 85 in which the rubber tube "f", acts as a spring to hold up the lever "h", and the moving part "m" effects the closing by pulling down on the lever through the medium 90 of the wire.

It is apparent that the heater with this cut-off may be attached to any sort of printing press that has an available moving part for giving the desired pull to the wire at the desired time, and that the heater as a 95 whole may be placed in a great variety of positions.

I do not wish to limit myself to the exact construction shown, it being apparent that there may be considerable variation in using 100 the principle of universal adjustment without departing from the spirit of my invention, or that a plurality of gas pipes might be employed, or that a different form of cut-off may be desirable on particular 105 styles of printing presses, etc.

What I claim is:

1. A portable gas heater adjustably mounted with reference to a printing press, 110 in combination with a reflecting baffle plate, for throwing heat upon freshly printed sheets, located or passing below said reflecting baffle plate.

2. A portable gas heater adjustably mounted with reference to a printing press, 115 in combination with a baffle plate or rectangular reflector for throwing heat on freshly printed sheets located or passing below, and an automatic cut-off for the gas supply.

3. A portable and adjustably mounted gas heater having a combined reflector and baffle plate, and a gas pipe with two parallel rows of flame holes, in combination 120 with a printing press, for the purpose of drying freshly printed paper.

4. A rectangular reflector adapted to throw heat over the entire surface of sheets of paper issuing from a printing press, and means for adjusting the position of said re- 115

reflector, in combination with a gas supply, led through a gas pipe having two parallel rows of flame holes.

5. A portable and adjustable gas heater, in close relation to a printing press, said heater having a plurality of parallel rows of flame holes, in combination with a reflecting surface, for securing a broad area or zone of heat, as set forth. 50

10. 6. A portable and adjustable gas heater, in close relation to a printing press, said heater having a plurality of parallel rows of flame holes, in combination with a reflecting surface, and with an automatic cut-off for the gas, as set forth. 55

15. 7. A portable and adjustable gas heater, in close relation to a printing press, said heater having a plurality of parallel rows of flame holes, in combination with a reflecting surface, an automatic cut-off for the gas supply, and an air mixing device. 60

20. 8. A portable gas heater, in close relation to a printing press, consisting of a metal pipe, with two parallel rows of flame 65
25 holes, preferably staggered, in combination with a reflecting surface, the entire heater being adjustable as to position with relation to the freshly printed paper issuing from a printing press.

30. 9. A reflecting gas heater, adjustably attached to a printing press, in combination with an air mixer, and a gas cut-off and a gas supply. 70

35. 10. In combination with a printing press, a portably arranged reflecting gas heater, whose heat supply comes through a suitably arranged gas pipe, said gas pipe provided with a plurality of parallel rows of holes, for the purpose of drying freshly 75
40 printed sheets issuing from said printing press. 80

45. 11. On a printing press, the combination of a portable and adjustable gas heater, a flexible rubber gas hose, and automatic means to control the flow of gas to the heater. 85

12. A gas valve on a printing press

heater, in combination with a wire and some moving parts of the press, for operating the valve by a pull on the wire, as set forth. 50

13. In a printing press heater, the combination of wire connected to a movable part of the press, a flexible gas tube, and a lever adjusted to pinch said flexible gas tube, thus controlling the flow of gas fuel to the heater. 55

14. In a portable and adjustable printing press heater, the combination of a gas supply, a flexible tube, and automatically operated means for opening and closing the tube to control the flow of gas. 60

15. In a printing press, the combination of an automatic cut-off, comprising a flexible tube and a compression lever, said compression lever connected by a cord or wire to and operated by a moving member of said printing press, and said cut-off connected to a portably arranged gas heater, as set forth. 65

16. A device for controlling the flow of gas fuel to a heater on a printing press in combination with a flexible rubber tube, and means for pinching the tube when the press stops, and releasing it when the press starts. 70

17. The combination of a portable gas heater for printing presses with a gas fuel supply, a flexible tube for said gas supply, a pinching device located on said flexible tube, and means for utilizing the movement of the printing press to either open or close 75
80 said pinching device, as set forth. 80

18. In a portably arranged printing press heater, the combination of a gas supply, a pilot light, a flexible tube, and means for opening and closing said tube in unison with 85
the stopping and starting of the press as set forth.

Signed at New York city in the county of New York, and State of New York, this fifteenth day of June, A. D. 1923.

CHARLES H. COCHRANE.
